UNITED STATES PATENT OFFICE.

VIOLA D. MUZZY, OF SPARTANSBURG, PENNSYLVANIA.

FLY-ESCAPE.

1,264,117.

Specification of Letters Patent.

Patented Apr. 23, 1918.

Application filed July 13, 1917. Serial No. 180,437.

To all whom it may concern:

Be it known that I, VIOLA D. MUZZY, a citizen of the United States, residing at Spartansburg, in the county of Crawford and State of Pennsylvania, have invented new and useful Improvements in Fly-Escapes, of which the following is a specification.

This invention relates to window screens, 10 and more especially to exits through which flies and other insects are permitted to escape from the apartment protected by the screen; and the object of the same is to produce a fly escape of this character applicable to the 15 screens in windows or doors or to the glass panes therein, and in this respect I reserve the broadest use of the invention.

The present invention is an escape which is made of transparent material so that it 20 does not interfere with the passage of light and which has an upwardly deflected nozzle or nipple and a body of such formation that it is directed toward the same.

Throughout the following specification I 25 refer to the attachment of an escape to a window screen, but at one point in the drawings the escape is shown as applied to a window sash, and I wish it to be distinctly understood that my invention is applicable to 30 either kind of sash or to the frame of a door at its corner, whether the transparent sheet of said door is of glass or screening. In other words, whatever the language herein-after employed, it is my intention that this 35 invention shall be applied to the frame of a screen, a sash, or a door. On this understanding I have used the letter F to designate the frame, and S and G to designate respectively the screen wire or the glass pane. Fur- 40 thermore, while not specifically illustrated in the drawings, it is possible that my escape could be attached to the frame F of a structure whose body was not transparent or translucent, or in other words an ordinary 45 door. In that case one corner of the panel would be cut out just inside the frame for the insertion of the escape itself as described below, and as the escape is of glass or other transparent material, it admits its own light 50 and attracts the flies on the interior of the building.

Details are set forth in the following specification, reference being had to the accompanying drawings wherein:—

55 Figure 1 is a perspective view of one corner of a window screen provided with my

improved escape, looking at the same from the inside of the screen, and this view includes a detail of the other upper corner of the screen as it is cut before the escape is attached thereto.

Fig. 2 is an enlarged detail of the escape for use on a screen, and Fig. 3 is a sectional detail of the escape and screen.

Fig. 4 is a vertical section of a window 65 sash frame, taken through one of these escapes which has been molded in its corner.

The escape is of glass or similar translucent material. It comprises a body 1 formed in the shape of a right-angular 70 triangle, and molded as part of and projecting from the plane of the body at its center is a tubular nipple 2 constituting a nozzle whose inlet end 3 where it unites with the plate is larger than its outlet end or mouth 4 75 and whose body preferably inclines slightly upward from its inlet to its outlet end when the plate is in place. When the escape is to be applied to a screen its plate has a row of perforations 5 along the hypotenuse 80 of the triangle as seen in Fig. 2, and these perforations may be carried along its other two sides as seen at 6, and a lacing wire 7 is passed through all perforations and the mesh of the screen. The latter may be cut 85 out near a corner with a triangular opening as seen at the left of Fig. 1, leaving a little of the screen remaining adjacent the contiguous sides of the frame at its corner, and the raw edges of the screen wire are turned 90 back all around the openings; and then when the lacing is applied it passes through the mesh of the screen all around the opening. By preference I use copper wire for the lacing, and it should be rather fine so that it will 95 be hardly noticed. I might say that it is possible to insert the right-angular edges of the plate 1 under the beading which holds the screen in the frame, and hold such edges in that manner without the lacing along them, 100 but in any event the lacing will be carried along the hypotenuse and the other edges will engage closely beneath or at least against the frame or its beading so that the triangular escape fits close in the corner of 105 the frame.

The escape when intended for application to the pane G of a window sash will be made in the same manner excepting that all perforations will be omitted. Along its hypotenuse it may then have a groove or rabbet 10 to engage over the edge of the glass G

2
where the latter is cut away on a diagonal line, and its right-angular edges will be inserted in the rabbet of the frame—the putty being removed for this purpose and replaced and painted so that the escape is hardly noticeable from either the exterior or the interior.

When now one or more of these escapes are applied to a sash, flies on the interior of 10 the building who usually fly toward and light upon the screen or glass in the forenoon or at other times of day when it is bright out of doors, crawl up the surface thereof and onto the escape, pass into its 15 larger inner end and along its body, and fly out its outlet end 4, and away; and later, especially toward evening when I have observed that they return and seek to reenter the house, they light on the outer face of the 20 screen or glass but will not find their way into the restricted mouths 4 of these escapes, and therefore, they are trapped outside the dwelling. The presence of one or more of these escapes in the corners of a sash will 25 hardly be noticed and will not interrupt the admission of light to a perceptible degree; and if they are applied to the glass G of a window sash, they admit practically no cold through their openings, even in the severest 30 weather. Care should be taken that the nozzles or nipples do not project so far beyond the screen or glass of a lower sash that they will strike the lower rail of the upper sash when said lower sash is raised or 35 when said upper sash is lowered; but if the body of the plate 1 is overlaid on the inner side of the sash or screen, the nozzle or nipple may project through the opening cut away therein and for some little distance,

without protruding beyond the plane of the 40 outer side of the sash.

What is claimed as new is:—

1. In a fly escape, the combination with a frame, and a sheet therein cut away on an oblique line at one corner of the frame; of a 46 triangular transparent plate seated in said corner with its right-angular edges engaging the frame and its hypotenuse overlying said oblique line, the plate being provided with a tubular nozzle having a larger inner 50 end opening through the plate and its body inclined upward and outward to a reduced mouth at the outside of the frame, and means for holding the plate in place.

2. In a fly escape, the combination with 55 a frame, and a screen therein cut away at one corner; of a triangular transparent plate seated in said corner with its hypotenuse overlapping the screen and perforated, a fastening device threaded through the perforations and the screen, and a tubular nozzle carried by the plate and projecting outward of the screen, for the purpose set forth.

3. In a fly escape, the combination with 60 the frame, and a screen therein cut at one corner with a triangular opening and the edges of the screen wire turned back around the three sides of said opening; of a triangular transparent plate seated in said corner and having two edges engaging the frame 70 and its hypotenuse overlapping the screen and all edges perforated, a tubular nozzle carried by the plate and projecting outward of the frame, and a wire laced through the perforations and the screen mesh.

75 In testimony whereof I affix my signature.

VIOLA D. MUZZY.
